UNITED STATES PATENT OFFICE.

HELEN F. BIEDEKAPP, OF WALTON, NEW YORK.

FLAT-SIDED WASHTUB.

Application filed November 22, 1922. Serial No. 602,638.

To all whom it may concern:

Be it known that I, HELEN F. BIEDEKAPP, a citizen of the United States, residing at Walton, in the county of Delaware and 5 State of New York, have invented certain new and useful Improvements in Flat-Sided Washtubs; and I do declare the following to be a full, clear, and exact description of the invention, such as will enable others 10 skilled in the art to which it appertains to make and use the same.

My invention relates to improvements in wash tubs and has reference more particularly to tubs which are used when clothing 15 is being passed through a wringer from one tub to another. The invention also relates to tubs which are used in connection with washing machines having power-operated wringers. During the wringing operation performed by a machine of this character, the usual circular tubs cannot be brought 20 into sufficiently close relation with each other and close enough to the washing machine, to prevent water from dripping onto the floor. The tubs only contact with each other at one point and water will drip from the wringer at opposite sides of this point. It is the object of my invention however 25 to provide a tub with two flat vertical side walls at right angles to each other, and a curved wall connecting the outer ends of said flat walls. Thus, the flat side of the tub may contact tightly with the corresponding side of another tub and the other flat 30 sides of the two tubs may be disposed adjacent to the washing machine, permitting the contacting walls of the two tubs to be disposed directly under the wringer, so that there is no danger of any water dripping 35 onto the floor. This arrangement is still further advantageous when more than two tubs must be placed side by side and clothes transferred from one to another and furthermore, when two of the tubs are used 40 in connection with a hand wringer, the ordinary wringer clamps may be employed to secure the adjacent flat sides of said tubs tightly in contact with each other.

With the foregoing in view, the invention resides in the novel subject matter herein-after described and claimed, the description being supplemented by the accompanying drawings:—

Figure 1 is a side elevation of a washing machine equipped with a power-driven

wringer and a tub support, showing two tubs constructed in accordance with my invention, upon the support beneath the wringer.

Fig. 2 is a top plan view of the tubs and support and a portion of the washing machine.

Fig. 3 is a side elevation of the support and a vertical sectional view of the tubs thereon.

Fig. 4 is a perspective view of one of the tubs.

In the drawings above briefly described, I have shown a washing machine 1, having a mechanically driven wringer 2 and below 70 this wringer I have illustrated a pair of my improved tubs 3 resting on the usual tub support 4.

Each of the tubs 3 is provided with two vertical flat side walls 5 at right angles 75 to each other and with a curved side wall 6 connecting the outer ends of said flat walls 5, the three walls being suitably secured to a bottom 7, all parts being preferably but not necessarily of galvanized sheet metal. 80

By employing two of my improved tubs in connection with a wringer, either hand or power-operated, it will be seen that two of the flat sides of said tubs may be disposed in tight contact with each other below 85 the wringer and that the contacting surface is sufficiently extensive to prevent any water whatever from dripping outside of the tubs. If the wringer is of hand-operated nature, the usual clamps may be employed to secure the flat sides of the tubs in contact 90 with each other. However, when the tubs are supported upon a stand 4 beneath a power-operated wringer associated with a washing machine, the sides of the tubs will 95 not be clamped in contact with each other but they will nevertheless maintain a sufficiently close engagement to prevent leakage of water onto the floor, as it drips from the wringer. The flat sides of the two tubs 100 which do not contact with each other are disposed adjacent to the washing machine 1 and thus said tubs may be positioned in sufficiently close relation with the machine, to prevent any dripping of water between 105 said tubs and machine, as now commonly occurs.

As excellent results may be obtained from the details disclosed, these details are preferably followed. However, within the scope 110

of the invention as claimed, minor changes in form, proportions and unimportant details, may be made.

I claim:—

5 As a new article of manufacture, a wash-tub having a bottom, two vertical flat side walls arranged at right angles to each other,

and an arcuate side wall connecting the outer ends of said flat walls, being inclined outward and upward. 10

In testimony whereof I have hereunto affixed my signature.

HELEN F. BIEDEKAPP.
